TAKISABURO MIZOGUCHI AND TAKEZO KAWAHARA, OF KANAGAWA-KEN, JAPAN.

FUEL-SAVING DEVICE.

Application filed May 31, 1927, Serial No. 195,492, and in Japan March 11, 1927.

This invention relates to new and useful improvements in fuel systems, for internal combustion engines, and one of the objects of the invention is to supply a quantity of steam 5 to the fuel charge from the carburetor, which steam is generated by heat contained in the burnt gases.

Another object of the invention is to supply a quantity of auxiliary atmospheric air 10 to the fuel charge from the carburetor.

A further object of the invention is to highly heat the fuel charge to form an extremely effective explosive mixture on its way to the intake manifold.

15 A still further object is to intimately intermix and break up the fuel charge into an extremely effective explosive mixture on its way to the intake manifold.

The accompanying drawings illustrate the 20 invention applied to internal combustion engines of motor vehicle by way of example, in which:

Fig. 1 is a front view partly in section.

Fig. 2 is a side view partly in section, and 25 Fig. 3 is a sectional view showing steam inlet and auxiliary air inlet in detail.

Referring to the drawings, we provide an intake manifold 1 and a mixing chamber 2 cast in one body, both communicating 30 through a port 3. The intake manifold 1 is of the usual type adapted to be applied to existing types of motors in place of conventional intake manifold generally used. The mixing chamber 2 is preferably of a hollow 35 spherical form and constructed in two sections and connected together by bolts or other suitable fastening devices, although it may be of any suitable forms and constructed in one body.

40 Within the mixing chamber 2 is enclosed a heater 4 with an inlet duct 5 and an outlet duct 6. This heater is substantially of hemispherical form with a depressed flat top, and is of such dimension as to provide an ample 45 space on the top for causing the explosive mixture to be intimately intermingled and providing suitable heating chamber between the wall of the mixing chamber and the wall of the heater as shown in Fig. 1, but it may 50 be of any suitable forms corresponding to the form of the mixing chamber, the top being flatly depressed for the above said purpose. An elbow 7 is connected to the exhaust manifold 8 by welding or other suitable means 55 and provided with a regulating valve 9, whereby any desired heating of the explosive

mixture may be attained so that it may be adjusted for changes in the weather conditions and different climatic conditions. The inlet duct 5 of the heater 4 is connected with the 60 elbow 7 by suitable means and the outlet duct 6 opens to atmosphere through suitable discharge pipe connected thereto, so that a portion of the burnt gas passing through the exhaust manifold 8 from the motor will enter 65 into the heater 4 through the elbow 7, the regulating valve 9 and the said inlet duct, and will heat the explosive mixture in the mixing chamber 2, and then discharge to atmosphere through the said outlet duct and the discharge 70 pipe.

The mixing chamber 2 is provided at the bottom with an inlet conduit 10 extending downward and having a lateral branch 11 for the carburetor connection.

75 The steam and the auxiliary air will be introduced into the inlet conduit 10 through any suitable means to intermix with the fuel charge from the carburetor. In the example illustrated in Figs. 1 and 3, at the under side 80 of the inlet conduit 10 is formed a casing 12 to which a cover 13 is tightly screwed. The cover 13 is provided with an internally extending tube 14 with a number of perforations 15 at the under portion thereof.

85 A steam inlet 16 with a regulating valve 17 and an internally extending tube 18 is connected to the cover 13 to communicate with the inlet conduit 10 by suitable means.

A steam generator 19 of suitable construction is so attached to the exhaust manifold 8 as to be heated by the burnt gas passing through the said exhaust manifold, and is supplied with some quantity of water through a pipe 20 from a tank (not shown) located in 90 suitable position and provided with such suitable means as a float control device in order to keep the water level constant, that is, to keep a constant water head. The steam generated in the steam generator 19 will enter 95 into the inlet conduit 10 through a pipe 21, a three-way cock or valve (not shown) interposed in the pipe line or branches thereof and adapted to establish the passage of the steam to the inlet conduit 10, or to discharge in atmosphere the steam and the steam inlet 16.

An auxiliary air inlet 22 with a regulating valve 23 is connected to the cover 13 to communicate with the casing 12. The atmospheric air will enter into the casing 12 110 through the regulating valve 23 where the air will be heated, and then the air will enter into

the inlet conduit 10 through the perforations 15 and the space 24 between the wall of the internally extending tube 18 of the steam inlet 16 and the wall of the internally extending tube 14 of the cover 13.

5 Thus, the above described means are adapted to introduce the steam and auxiliary air, both at the same time or either one as desired, into the fuel charge from the carbureter.

10 From the foregoing description, the operation and functions of the improved fuel saving device will be understood. With the heating and mixing system according to the invention, it will be seen that the fuel charge from the carbureter will be highly heated by means of the heater with the steam and, the auxiliary air introduced therein and broken up into more effective explosive mixture 15 through an eddying action which takes place in the top space of the mixing chamber. The auxiliary air supply to the fuel charge from the carbureter is found necessary and considerably effective to form the most effective 20 explosive mixture even with well designed carbureters. The fact that the burnt gas passing through the exhaust manifold is ejected into atmosphere through the heater will have the same effect as an increase of the 25 diameter of the exhaust manifold, so that back pressure in the motor cylinder will be reduced. Further, the carbureter will be heated by radiation and conduction of heat from the mixing chamber, the carbureter 30

being connected adjacent the mixing chamber, so that the operation of the carbureter will be considerably improved. This improved system is extremely economical and improves operation of the motor, more particularly starting of the motor, and may be 35 applied to any type of motors now generally in use.

It will of course be understood that numerous details of the construction shown may be altered without departing from the spirit of 40 this invention as defined by the appended claim.

Having now particularly described and ascertained the nature of our said invention and in what manner the same is to be performed, we declare that what we claim is:

45 A fuel saving device for internal combustion engines comprising an exhaust manifold, an intake manifold, a heater substantially of hemispherical form with a flat top, a mixing 50 chamber substantially of spherical form in outline connected to said intake manifold and enclosing said heater therein, means for supplying steam to the explosive mixture in the inlet duct of said mixing chamber and means 55 with a regulating valve for drawing supplementary air into the inlet duct of said mixing chamber.

60 In testimony whereof we affix our signatures.

TAKISABURO MIZOGUCHI.
TAKEZO KAWAHARA.
